UNITED STATES PATENT OFFICE.

CEPHAS LITTLE BARD, OF SAN BUENAVENTURA, CALIFORNIA.

REIN-GUARD.

SPECIFICATION forming part of Letters Patent No. 352,674, dated November 16, 1886.

Application filed June 15, 1886. Serial No. 205,249. (No model.)

To all whom it may concern:

Be it known that I, CEPHAS LITTLE BARD, of San Buenaventura, in the county of Ventura and State of California, have invented 5 certain new and useful Improvements in Rein-Guards; and I do hereby declare the following to be a full, clear, and exact description of the invention, such as will enable others skilled in the art to which it appertains to 10 make and use the same.

My invention relates to an improvement in rein-guards, and more particularly to devices for preventing the reins from becoming fouled under the adjacent ends of the whiffletrees, 15 where a span of horses is attached to a vehicle. Hitherto this has been partly accomplished by means of leather disks secured to the ends of the whiffletrees, which have been undesirable because of their clumsy and un- 20 sightly appearance. It is, however, a matter of no inconsiderable importance that there should be some means of effectually preventing the fouling of reins in the above-mentioned manner, since it has proved not only a 25 great annoyance, but in many instances injury to life and property has resulted from it.

The object of my present invention is to provide a neat, cheap, efficient device for preventing the reins from becoming fouled.

30 A further object is to provide a combined rein-guard and trace-fastener, which may serve also to limit the vibratory motions of the whiffletrees.

With these ends in view my invention consists in a flexible band or strap connecting the 35 adjacent whiffletree-tips.

My invention further consists in certain features of construction and combinations of parts, as will be hereinafter described, and 40 pointed out in the claims.

In the accompanying drawings, Figure 1 is a detached view of the combined guard and trace-fastener. Fig. 2 is a view of a slightly modified form. Fig. 3 is a view of the same 45 applied to the whiffletrees, and Fig. 4 represents a modified form.

A represents the body portion of the rein-guard, which is in effect a whiffletree-coupler.

It consists of a strip of flexible material— 50 leather, rubber, &c., for example—and is provided at or near each end with a slit or open-

ing, a, adapted to be slipped over the eye portion of the tip b on the end of each whiffletree B. It is permanently attached to the tips by crowding its slotted ends over the ends of the 55 tips, and, if desired, the slits a may be partially closed by means of a thread or cord passing through perforations in the opposite edges of the slit. The ends of the guards, when on the tips and the traces adjusted, form 60 bearing-washers, which protect the traces from chafing against the ends or sharp edges of the ends of the whiffletrees.

The portion of the guard between the ends of the whiffletrees should have the requisite 65 amount of slack to allow the ends of the whiffletrees their normal play.

By making the guard of strong tough material the guard may serve as a stop to regulate the play of the whiffletrees, the ordinary ring- 70 straps being in this instance dispensed with, and the appearance of the running-gear thereby improved.

In my preferred form (shown in Fig. 1) the 75 ends of the guard are prolonged at right angles, or nearly so, to the body of the same, and are tapered, as shown at a', to serve as trace-fasteners.

When in position on the whiffletree-tips, the 80 body of the guard A will assume a rearwardly-bent position in a horizontal plane, and the ends a' will bend over the traces and extend downwardly through the eyes of the tips.

It will be observed that the above device 85 forms a perfect guard against the passage of the reins beneath the ends of the whiffletrees, while at the same time it combines in itself trace-fasteners and stops which prevent the vibratory play of the whiffletrees.

The modified form shown in Fig. 2 consists 90 of a guard portion, A, having the trace-fastening ends formed by a prolongation of the body in the direction of its length.

The second modified form (shown in Fig. 4) 95 consists of the body portion only, the trace-fastening ends being omitted.

I make no claim in this application to a strip of leather or other suitable material provided with a slit or opening adapted to slip over the eye portion of the whiffletree-tip, and a thread 100 or cord adapted to partially close the slit or opening after the fastener is in position, as the

same forms the subject-matter of my pending application No. 205,248.

It is evident that the curve of the body portion might be downward or forward instead of rearward, as shown, and that the guard might be made in various other forms than those shown without departing from the spirit and scope of my invention; hence I do not wish to limit myself strictly to the construction herein set forth; but,

Having fully described my invention, what I claim as new, and desire to secure by Letters Patent, is—

1. The combination, with a pair of whiffle-trees, of a flexible strap or band secured to and connecting the adjacent ends of the whiffletrees, and forming a rein-guard, substantially as set forth.
2. The combination, with a pair of whiffle-trees, of a flexible strap or band provided with slits or openings in its ends adapted to be slipped over the tips of the adjacent ends of the whiffletrees, for the purpose substantially as set forth.
- 25 3. The combination, with a pair of whiffle-

trees, of a flexible band or strap provided with slits or openings adapted to be slipped over the tips of the adjacent ends of the whiffletrees, and having its ends prolonged to form trace-fasteners, substantially as set forth.

4. A rein-guard consisting, essentially, of a flexible strap or band adapted to connect the adjacent ends of a pair of whiffletrees, and having trace-fastening ends projecting at right angles, or nearly so, to the body portion, substantially as set forth.

5. The rein-guard consisting essentially of the body portion with slits formed near the ends thereof, and adapted to couple the adjacent ends of the whiffletrees, and the end portions tapered and adapted to bend over the traces and extend through the eyes in the whiffletree-tips, substantially as set forth.

In testimony whereof I have signed this specification in the presence of two subscribing witnesses.

CEPHAS LITTLE BARD.
